SAFETY MECHANISM FOR DYE KETTLES
AND THE LIKE

Joseph H. Higginson and Homer C. Riggs, Andover, Mass., assignors to Riggs & Lombard, Inc., Lowell, Mass., a corporation of Massachusetts

Application January 7, 1944, Serial No. 517,460

3 Claims. (Cl. 220—40)

1

This invention relates to safety mechanism for closing an opening in a receptacle containing fluid under pressure, and the general purpose of the invention is to provide mechanism for preventing release of the cover so long as fluid pressure in the receptacle is maintained.

More particularly the invention relates to improvements in stock dye kettles, or other receptacles, containing hot dye, or other liquid, which is circulated under pressure through the stock in the kettle and which are provided with a sampling hole or aperture through which a sample of the stock in the kettle can be obtained, or the condition of the material in the receptacle can be determined.

In usual dye kettles or the like the aperture is provided with a cover which is clamped firmly over the aperture by detachable means so that the cover can be removed to obtain access to the material within the kettle. If the cover is released before the fluid pressure of the material is released the hot vapors issuing from the aperture is apt to injure the operator.

The principal object of the present invention is to provide a safety cover construction for the sampling hole or aperture in the dye kettle or the like, or more broadly stated to provide a cover mechanism for closing an opening in a receptacle containing fluid under pressure which cannot be released or removed so long as pressure in the dye kettle or receptacle is maintained.

A further object of the invention is to provide mechanism for more effectively clamping the cover upon the opening and for maintaining the cover in such clamped position until fluid pressure in the container is released.

These and other objects and features of the invention will more fully appear from the following description and the accompanying drawings and will be particularly pointed out in the claims.

Preferred embodiments of the invention are illustrated herein as applied to the cover plate of a stock dye kettle of the type illustrated and described in our prior Patent No. 2,275,818 granted March 10, 1942, but is adapted to other types of dye kettles in which the hot dye liquor is circulated in a closed container provided with a sampling hole. Inasmuch as the general construction of the dye kettle is disclosed in our prior patent aforesaid only such upper portion of the kettle and cover is illustrated herein as is necessary to illustrate the novel construction forming the subject matter of the present invention.

In the drawings:

Fig. 1 is a view, mainly in vertical section, of

the upper portion of the dye kettle and the cover plate therefor provided with a sampling hole and cover mechanism embodying the invention;

Fig. 2 is a plan view of the same, portions of the cover plate being broken away;

Fig. 3 is an enlarged detail view in diametrical vertical section showing the cylindrical wall surrounding the sampling hole and cover therefor and the preferred mechanism for locking the cover in closed position; and,

Fig. 4 is an enlarged side elevation of the construction shown in Fig. 3.

Fig. 5 is a view partly in vertical section of a modified form of mechanism for locking the cover to the sampling hole in closed position.

The dye kettle, which may be of any suitable construction preferably of the type illustrated in our patent aforesaid, for containing the stock to be dyed with means for circulating hot dye liquor through the stock is provided with a vertical cylindrical wall 1 and the stock is supported upon a suitable removable carrier having a central tubular perforated standard through which heated dye liquor is forced under pressure into and upon the material on the carrier. The upper end of the standard 2 has secured to it a clevis adapted to be engaged by means for lifting the carrier out of the kettle. The cylindrical wall 1 is provided adjacent its upper end with a peripheral

angle bar flange 3 having a rib 4 spaced from the wall 1 to provide a seat for a gasket 5 of suitable material upon which the peripheral portion of a cover plate 6 is mounted. The cover plate 6 preferably has an upwardly concave central portion and a vertical wall 7 adjacent its periphery and is reinforced by radial girders 8 welded there-

to and to said peripheral wall and to a central hub 10. A circular top plate 9 desirably is mounted upon the girders 8 to form a finished cover plate construction. The central hub 10 is secured by a bolt 11 to the apex portion of diverging lifting arms 12 having means (not shown) for swinging the cover plate construction upwardly out of the path of the stock carrier of the kettle when the latter is lifted out of the kettle.

A flange 13 complementary to the flange 3 on the upper end of the kettle extends outwardly from the wall 7 and overlies the periphery of the cover plate 6. Suitable means are provided for clamping the cover plate construction upon the gasket 5, such as equally spaced clamps 14 pivotally mounted in brackets 15 secured to the angle bar flange member 3 and provided with a screw 16 having a head 17 to engage the flange 13 and

actuating handles 18.

The top plate 9 has a suitable opening 19 to

permit access to the cover for a sampling hole 20 in the cover plate located in convenient proximity to the periphery of the kettle. A cylindrical wall 21, which is welded to the cover plate 6, surrounds the periphery of the aperture 20.

The cover 22 for the sampling hole comprises a flat plate having a downwardly extending flange 23 which telescopically surrounds the peripheral wall 21 of the sampling hole.

Suitable means are provided for locking and maintaining the cover in closed position so long as fluid pressure is maintained in the kettle or other receptacle.

In the particular construction illustrated in Figs. 1 to 4 a ring 24, which is welded to or formed integral with the cover, is spaced concentrically a suitable distance from the flange 23 to form a seat for a gasket 25 to engage the upper end of the peripheral wall 21 of the sampling hole 20.

The wall 21 and cover flange 23 desirably are provided with suitable interengaging members adapted when interengaged to hold or clamp the gasket of the cover tightly upon the peripheral wall 21 of the sampling hole. In the preferred construction the interengaging members comprise a plurality of pairs of diametrically opposite pins 26 which are mounted upon and extend outwardly from the peripheral wall 21 of the sampling hole. The flange 23 of the cover is provided with bayonet slots adapted to engage the respective pins 26 and comprise a vertical entrance 27 which communicates with a laterally and slightly upwardly extending slot 28 so that when the cover is placed upon the wall 21 of the sampling hole the pins 26 will enter the vertical slot and upon rotative movement of the cover in a proper direction will force the cover downwardly so as to compress the gasket 25 firmly upon the upper end of the wall.

Suitable means are provided for retaining the interengaging members in engagement so long as fluid pressure is maintained in the kettle. In the preferred construction illustrated a series of ratchet teeth 29 are formed on the under face of the outwardly extending rim 30 of the cover and are adapted to be engaged by a suitable latch 31 which is forced into such engagement by the fluid pressure within the kettle.

In the construction illustrated the latch 31 is integral with or is secured to a cross head 32 which is reciprocably mounted in a sleeve 33 provided with an externally threaded lower end which engages a block 34 which is welded or otherwise secured to the cover plate 6. A lever 35 extends diametrically through suitable openings in the sleeve 33 and cross head 32 and is fulcrumed upon a pin 36 which is mounted in a boss extending from the wall of the sleeve 33. The lever 35 is provided with a slot 37 which is engaged by a pin 38 which is mounted in the cross head and extends through the slot 37. The opposite end of the lever 35 is likewise provided with a slot 39 which is engaged by a pin 40 which is mounted in the bifurcated end portion of a piston rod 41. The piston rod 41 is mounted in a suitable packing gland (not shown) in the block 34 and is provided at its lower end with a relatively thin disk 42 which engages a flexible diaphragm 43.

The periphery of the diaphragm is clamped between upper and lower rings 44 and 45 by a series of suitably spaced screws 46. The ring 44 is so constructed that its upper surface will engage the inclined under face of the cover plates 6 and the lower face of the ring will be in hori-

zontal position at right angles to the axis of the piston rod 41. The ring 44 may be welded or otherwise secured to the under face of the cover plate 6.

5 A coiled spring 47, which surrounds the latch 31 and is interposed between the upper end of the cross head 32 and a flange 48 on the sleeve 33, normally forces the latch downwardly out of ratchet-engaging position and likewise causes the lever 35 to depress the diaphragm into the position illustrated in dotted lines in Fig. 3.

10 In the operation of the device the carrier of the kettle is loaded with stock to be dyed, or otherwise treated, while the cover plate is held in open position. The cover plate is then swung to closed position and secured firmly upon the kettle by the clamps 14.

15 The hand hole cover 22 is then lowered through the opening 19 in the upper plate 8 of the kettle cover with its flange 23 telescopically surrounding the peripheral wall 21 of the sampling hole. The cover is then manipulated to cause the pins 26, which extend outwardly from the wall 21, to enter the vertical portion 27 of the bayonet slots. The cover is then rotated in a direction to cause the pins to ride on the inclined lower wall of the portion 28 of the bayonet slot, thus forcing the cover and its gasket 25 downwardly and firmly sealing it upon the upper end of the wall 21 of the sampling hole.

20 When the hot dye liquor is forced into the kettle the vapors therefrom produce sufficient fluid pressure in the upper portion of the kettle to force the diaphragm 43 upwardly thereby causing the piston rod 41 to raise the outer end of the lever 35 and raise the latch into engagement with the ratchet teeth 29 on the under face of the projecting rim 30 of the cover, thus locking the cover against reverse rotation and maintaining the interengaging members of the cover in locked position so long as fluid pressure in the kettle is maintained.

25 By reason of this construction the cover is absolutely prevented from removal until release of the fluid pressure in the kettle when the spring 47 will force the latch downwardly into an operative position. The rim of the cover can then be readily grasped by the hands of the operator and the cover reversely rotated and removed to permit sampling of the stock in the kettle or examination of the conditions which obtain within the kettle.

30 It will be noted that by reason of the ratchet and latch construction the cover may be rotated in a direction to lock the cover firmly in place even after fluid pressure has been generated in the kettle as the latch will slide over the inclined surface of the ratchet teeth and under such circumstances the cover cannot be rotated in the reverse direction to disengage the bayonet slot connection.

35 A modified form of the invention for locking the cover to the sampling hole in closed position is illustrated in Fig. 5 and comprises broadly an arm which is pivotally mounted upon the peripheral wall which surrounds the sampling hole and extends diametrically over the cover and is connected centrally thereto with clamping means engaging the opposite end of the arm to hold the cover in closed position and means operable by the fluid pressure in the kettle to prevent release of the clamping means so long as fluid pressure is maintained in the kettle.

40 As illustrated in Fig. 5 a vertical ear or ears 49 are welded to the peripheral wall 21 of the

opening 20 and a lever 50, which is pivotally mounted on the ear or ears 49, extends upwardly and thence diametrically across the cover 22. The lever 50 is provided with a stud 51, located centrally over the cover 22, the lower end of which extends into the space between a pair of bosses 52 and 53 which are preferably integral with and extend upwardly from the central portion of the cover. The stud 51 is pivotally connected to the bosses 52 and 53 by a pin 54. The upper end of the stud extends through the lever 50 and is secured thereto by a transverse pin 55. The free end of the lever is provided with a bifurcated end portion 56 and the upper edge of the lever is provided with a curved portion 57 which forms a seat for a hand wheel 58 the hub of which is provided with a screw threaded bore in which is mounted a screw threaded rod 59 having at its lower end an integral enlarged cylindrical portion 60 which is journaled on a stud 61 which is mounted in ears 62 which are welded to and extend outwardly from the peripheral wall 21 which surrounds the sampling hole 20. The cylindrical portion 60 of the rod 59 is provided with a series of ratchet teeth 63 adapted to be engaged by a locking pawl 64 which is slidably mounted in the upper wall of an inverted hollow cylindrical boss 65 which is welded to the cover plate 60 of the kettle. The locking pawl 64 is forced into locking position by means subject to the fluid pressure within the kettle which, as illustrated in Fig. 5, is similar to that shown in detail in Fig. 3. In the construction shown in Fig. 5 the lower end of the locking pawl 64 has an enlarged cylindrical portion 66 which, like the piston rod 41, shown in Fig. 3, is integral with or has secured to it a disk 42 which engages a flexible diaphragm 43 which is mounted on the under face of the ring 44 and clamped upon it by a ring 45 and screws 46.

In the operation of the device shown in Fig. 5 the lever 50, which carries the cover 22, is swung to closed position, as illustrated in full lines in Fig. 5, so that the cover fits tightly upon the gasket 25 and clamps the latter firmly upon the upper end of the peripheral wall 21 of the sampling hole. The rod 59 is swung about its pivot 61 into the bifurcated end of the lever 56 and the hand wheel 58 then screwed down tightly clamping the cover in place. When fluid pressure builds up in the kettle the diaphragm 43 is forced upwardly thereby raising the locking pawl 64 into engagement with a tooth of the ratchet 63, thus preventing the clamping rod 59 and hand wheel 58 from being swung out of engagement with the lever 50 so that the cover cannot be removed until release of the fluid pressure in the kettle.

It will be noted that the bifurcation in the end of the lever extends somewhat beyond the vertical position of the rod 59 and that the lower end of the hub of the hand wheel 58 is circularly curved to fit upon the complementary circular seat 57 upon the lever 50. This enables the rod 59 to be swung sufficiently to cause a proper tooth in the ratchet to be engaged by the pawl 64 and hold the cover down upon the gasket 25 with sufficient pressure to prevent the escape of any gaseous fluid under pressure from the sampling hole.

Suitable means are provided for releasing the pawl when fluid pressure in the kettle is relieved. This desirably is accomplished by a coiled spring 67 which is interposed between the cylindrical portion 66 of the pawl and the upper wall of the

boss 65. When fluid pressure in the kettle is released the spring 67 will force the pawl 64 downwardly out of engagement with the ratchet teeth 63. The hand wheel 58 may then be rotated in a reverse direction sufficient to enable the rod 59 to be swung outwardly over the end of the lever 50 to dotted position illustrated in Fig. 5. The lever 50 may then be swung upwardly and laterally thus removing the cover to the dotted position illustrated in Fig. 5, thereby uncovering the sampling hole and permitting access to the contents of the kettle. This construction presents certain advantages over that illustrated in Figs. 1-3 in that the cover is always connected to the cover plate of the kettle instead of being freely removable from it.

It is obvious that the invention is applicable to other types of stock dyeing kettles or to any type of receptacle containing fluid under pressure with respect to which it is desirable to have an opening for determining the condition of the contents of the receptacle.

It is to be understood that the preferred embodiment of the invention shown and described herein is of an illustrative character and that other forms of interengaging and locking mechanism may be employed within the spirit and scope of the claims.

Having thus described the invention, what is claimed as new, and desired to be secured by Letters Patent, is:

1. Safety closure mechanism for the sampling hole in a stock dye kettle or the like containing fluid under pressure and having a cover plate provided with an outwardly extending cylindrical wall surrounding the sampling hole comprising a cover for said sampling hole having a flange telescopically and rotatably fitting said wall, cooperating means on said cover flange and wall operable upon rotation of the cover in one direction to clamp the cover on said wall and upon rotation in the opposite direction to release the cover therefrom, a peripheral rim on said cover provided with a series of recesses, a latch reciprocably mounted on the cover plate of said kettle in cooperative relation to the recess in said rim, and means operable by the fluid under pressure in said kettle to maintain the latch in engagement with a recess in said rim so long as fluid pressure in the kettle is maintained.

2. Safety closure mechanism for the sampling hole in a stock dye kettle or the like containing fluid under pressure and having a cover plate provided with an outwardly extending cylindrical wall surrounding the sampling hole, comprising a cover for said sampling hole having a flange telescopically and rotatably fitting said wall, a gasket between the end of said wall and cover, complementary bayonet and slot connection on said flange and wall movable by rotation of said cover into interengagement in which slots on the cover are so inclined as to clamp the cover and gasket upon said wall, a peripheral rim on said cover provided with a series of ratchet teeth, a latch mounted on the cover plate of said kettle adapted to engage the teeth of said ratchet, and means operable by fluid under pressure in said kettle to maintain the latch in engagement with the ratchet so long as pressure in the kettle is maintained, and means withdrawing the latch from such engagement upon release of said fluid pressure to permit reverse rotation and removal of said cover upon release of said fluid pressure.

3. Closure mechanism for the sampling hole 75 of a stock dye kettle or the like containing fluid

under pressure and having a cover plate provided with an outwardly extending cylindrical wall surrounding a sampling hole, comprising a cover for said sampling hole having a flange telescopically and rotatably fitting said wall, a gasket between the end of said wall and cover, complementary bayonet and slot connection on said flange and wall movable by rotation of said cover into interengagement in which slots on the cover are so inclined as to clamp the cover and gasket upon said wall, a peripheral rim on said cover provided with a series of ratchet teeth, a latch reciprocably mounted on the cover plate of said

kettle adapted to engage the teeth of said ratchet; a latch-operating lever mounted on the cover plate of said kettle, a diaphragm within said kettle subject to the fluid pressure therein having means engaging said lever operable to maintain said latch in engagement with said ratchet teeth so long as pressure is maintained in said kettle, and a spring acting upon said latch to withdraw it from engagement with said ratchet teeth upon release of fluid pressure in the kettle.

JOSEPH H. HIGGINSON.
HOMER C. RIGGS.
